UNITED STATES PATENT OFFICE

2,484,388

NECKTIE

Samuel Reiner, Brooklyn, N. Y.

Application May 23, 1947, Serial No. 750,024

4 Claims. (Cl. 2—146)

1

This invention relates to improvements in neckties and more especially to four-in-hand neckties.

One of the chief complaints with such neckties is the tendency of the knot to slip after being tied and placed in the desired position in the collar unless the tie is knotted more tightly than is good for it; and this tendency is greater with ties whose outer covering or facing material is smooth. Ties adapted for tying relatively small knots are purposely made of softer material and are less bulky than ties for large knots; and such are especially prone to slip quite readily unless the knot is tied tightly, in which case the knot is not smooth and full and the front of the tie immediately below the knot does not dimple or drape properly.

I have found that a tie may be made with the desired facing or outer covering material and with the knot-tying portion of any desired slenderness or bulk to provide a knot of the desired character while still providing efficient means preventing knot slippage, without undue strain, wear or creasing of the knot-tying portion.

A further object of the invention is to provide a necktie which may be tied in a smooth full knot while the front end as it leaves the knot will properly dimple to provide a pleasing appearance.

A further object of my invention is to provide a tie of the character described which will withstand repeated usage, pressing and cleaning without undue deterioration.

Further objects and advantages of the invention will more fully appear from the following description taken in connection with the accompanying drawing, which shows by way of example, the preferred embodiment of the invention.

Referring to the drawing:

Fig. 1 is a plan view of a tie embodying the invention showing the back of the rear portion and front of the front portion;

Fig. 2 is a partial front elevational view of the tie shown in Fig. 1, tied in the usual manner when worn;

Fig. 3 is a somewhat enlarged cross-sectional view of the rear or tail end of the tie, taken on the line 3—3 of Fig. 1;

Fig. 4 is a somewhat enlarged cross-sectional view of the front end and rear or tail end of the tie, taken on line 4—4 of Fig. 2; and

Fig. 5 is a somewhat exaggerated longitudinal sectional view of the lining portion in the tail or rear end of the tie.

Referring more particularly to Figs. 1 and 2, the facing or outer fabric body cover of the tie,

2

designated 1, extends the full length of the tie and in accordance with usual practice is preferably cut on the bias and may comprise one or more pieces suitably sewn together. The lengthwise extent of the tie conveniently may be considered as comprising a front end 2, a rear or tail end 3 and an intermediate or neck-encircling portion 4. When the tie is worn and knotted as at 5 a section 6 of the front end becomes the knot-tying portion and a section of the tail end included in the knot 5 becomes the knot-encircled portion or center about which the knot is tied.

The front end 2 is provided with a suitable lining 7 which is shown as the usual bias cut fabric and extends throughout the front end and throughout the major portion of the neck-encircling portion. As a lining for the knot-encircled or knot-center portion I provide a special lining portion 8 somewhat thicker than the lining portion 7 and the special features of which will be more fully described hereinafter whose inner end is stitched or suitably connected to the inner end of the lining portion 7 at 9. The lining portions 7 and 8 are disposed within the fabric body or casing 1 and secured thereto in the usual manner by loose stitching such as 10 which permits relative longitudinal yield between the body and lining.

The lining portion 8 is an elastic webbing comprising a plurality of longitudinally extending rubber or the like elastic strands 11 interwoven with laterally extending fabric threads 12 and providing laterally extending ribs 13. Said elastic webbing is disposed within said body in un tensioned condition. I have found that the cross ribs, which present a surface corrugated in a longitudinal direction, resist slipping of the knot along the knot-encircled portion. Additionally, the web being stretchable longitudinally and the elastic strands tending to return it to its un-stretched length produces a gripping action between the knot-tying and knot-encircled portion. That is, when the knot is tied and forced upwardly into position the tail end is stretched and elongated and the knot is tied throughout, with the result that the elastic nature of the webbing in a longitudinal direction only while being substantially non-elastic in the direction of width results in a reaction tending to pull the knot upwards or hold it upwards in tied position.

It will be seen from the foregoing that I have provided a tie which is readily made in the usual manner of assembly and sewing and which has the conventional outer appearance; but which provides a full smooth knot which will not slip

and which dimples at and drapes gracefully below the knot.

Having thus described my invention with particularity with reference to the preferred embodiment of the same, and having referred to some of the possible modifications thereof, it will be obvious to those skilled in the art after understanding my invention, that other changes and modifications may be made therein without departing from the spirit and scope of the invention, and I aim in the appended claims to cover such changes and modifications as are within the scope of the invention.

What I claim is:

1. A necktie comprising an outer fabric body having a front end providing a knot-tying portion and a rear end providing a knot-center portion around which said knot is adapted to be tied and an intermediate neck-encircling portion, and a lining disposed within said body extending throughout said knot-center portion and loosely stitched thereto with the adjacent portion of said outer fabric body smoothly and freely disposed thereover, said lining being a ribbed fabric webbing with the ribs extending in a transverse direction to thereby present cross ribs which when the said lining is tightly encircled by a tied knot is manifest through said outer fabric body and resists the slipping of said knot in a direction longitudinally of said knot-center portion.

2. A necktie comprising an outer fabric body having a front end providing a knot-tying portion and a rear end providing a knot-center portion around which said knot is adapted to be tied and an intermediate neck-encircling portion, a lining disposed within said body extending throughout said knot-center portion with the adjacent portion of said outer fabric body smoothly and freely disposed thereover, said lining being a relatively heavy-bodied ribbed webbing having fabric ribs extending in a transverse direction to thereby provide a corrugated surface apart from and disposed within said outer fabric body which manifests itself through said outer fabric, thereby resisting movement longitudinally thereof of a knot tied thereabout, and a less heavy-bodied fabric lining extending throughout said knot-tying portion and connected to said first lining portion.

3. A necktie comprising an outer fabric body having a front end providing a knot-tying portion and a rear end providing a knot-center portion around which said knot is adapted to be tied and an intermediate neck-encircling portion, a

first lining portion disposed within said knot-tying and neck-encircling portions, and a second lining portion extending throughout said knot-center portion and secured to said first lining portion, said second lining portion being an elastic webbing comprising laterally extending fabric threads and a plurality of interwoven elastic strands extending in a longitudinal direction, said elastic webbing being disposed within said body in substantially untensioned condition and loosely stitched thereto, whereby when longitudinal tension is imposed upon said knot-center portion, in the normal process of tying said knot, said elastic webbing is stretched lengthwise and is firmly gripped by said knot-encircling portion to thereby hold said knot against slippage.

4. A necktie comprising an outer fabric body having a front end providing a knot-tying portion and a rear end providing a knot-center portion around which said knot is adapted to be tied and an intermediate neck-encircling portion, a first lining portion disposed within said knot-tying and neck-encircling portions, and a second lining portion extending throughout said knot-center portion and secured to said first lining portion, said second lining portion being an elastic webbing comprising a plurality of relatively thin elastic strands extending in a longitudinal direction interwoven with fabric threads extending in a transverse direction and providing lateral ribs, said elastic webbing being disposed within said body in substantially untensioned condition and loosely stitched thereto, whereby when longitudinal tension is imposed upon said knot-center portion, in the normal process of tying said knot, said elastic webbing is stretched lengthwise with a resultant increased longitudinal spacing of said ribs, to thereby hold said knot against slippage.
